DANIEL L. CHANDLER, OF BOSTON, MASSACHUSETTS, ASSIGNOR TO FRED H. ROWE, OF BOSTON, MASSACHUSETTS

COIN TIME SAVINGS BANK

Application filed January 8, 1929. Serial No. 331,029.

My present invention relates to coin savings banks, and more particularly to a coin time savings bank in the form of a clock.

This invention is designed for the purpose of stimulating the practice of saving money by a systematic principle, either for the adult or the child. For many years past it has been a recognized fact that small coins were more easily saved if in so doing some simple mechanical device was used in which the child derived some measure of pleasure in the mechanical movement of the device into which his coin was dropped, but in most prior devices of this kind it was practically impossible to actually tell whether or not the child had dropped his or her coin in the bank as he or she had been instructed.

In my present device, the clock is so arranged together with other appropriate mechanism that the face of the clock is covered unless a coin has been dropped in the bank each day. Once every twenty-four hours the mechanism of the clock attachments resets the disk so that the face of the clock is covered and a new coin each morning must be inserted before the time is ascertainable. By such an arrangement, the clock always shows whether or not the child has deposited a coin as instructed, or in the case of the adult, a coin must be deposited if the time is to be read, thereby creating an incentive to regular and constant savings in varying amounts from one cent upward.

The principal object therefore, is a coin time savings bank for use by both the child and the adult.

In the drawings accompanying this specification,

Fig. 1 is a front elevation showing the clock in a position corresponding to the position presented following the dropping of a coin,

Fig. 2 is a fragmentary side elevation corresponding to Fig. 1, but showing the face of the clock closed prior to the dropping of a coin,

Fig. 3 is a plan section taken on the line 3-3 of Fig. 2,

Fig. 4 is vertical section taken on the line 4-4 of Fig. 3,

Fig. 5 is a detail of the trip mechanism, and

Fig. 6 is a perspective view of the coin box into which the coins drop after having passed through the clock mechanism.

Referring to the drawings, 10 indicates a rectangular box composed of metal or its equivalent and comprised of five sides, the back or sixth side being open but adapted to receive an inclosing plate 11 extending part way down the back and provided with flanged edges along the top or sides adapted to be secured to the box 10 in any suitable manner as by countersunk screws 12. A coin box 13 is provided as a receptacle for coins sliding into the box 10 adjacent the bottom of said box 10 and directly below the back plate 11 such that the outer face 14 is in vertical alignment with the said back plate 11 when the coin box 13 is in a closed relation to the box 10. A hinged door 15 swinging on the hinge member 16 and pintle 17 is provided with any suitable lock as indicated at 18 such that the entire coin box 13 may be easily withdrawn and taken to the savings bank for the purpose of crediting its contents on the depositor's bank book. An inlet coin opening 19 is further provided in the coin box 13 which is in alignment with other apparatus hereinafter described for the purpose of receiving the coins that are passed through the bank and which actuate certain other mechanism as will be described later.

Centrally disposed in the box 10 is a horizontal shelf 20 having upturned flanges 21 adapted to be held to the sides of the box 10 by means of screws 21. Attached to such shelf 20 is a standard clock 22, the face of which is in alignment with an opening 23 provided in the front of the box 10 over which is mounted a crystal 24. At the rear of the clock 22 is an additional gear train comprising a pinion 25 secured to an extension shaft directly connected to the hour hand of the clock 22 and indicated at 26. Pinion 25 engages with an intermediate gear 27 on which is another pinion 28 engaging with a final gear 29 upon which is located an offset trip pin 30. The gear ratio of the gear train is so proportioned that the gear 29 on which the pin 30 is located revolves once in every twenty four revolutions of the hour hand shaft extension 26.

To one side of the clock 22 and also mounted on the shelf 20 is a pair of bearing members 31 adapted to receive a horizontal shaft 32 journalled therein. Attached to the front 5 end of this shaft 32 is an arm 33. At the extreme left end of the arm 33, as viewed in Fig. 4, is a coin receptacle composed of sheet metal as indicated at 34. The two sides and back of this receptacle 34 are closed as well 10 as a portion of the under side such that when a coin is deposited through a slot in the top of the box 10 directly above the receptacle 34, it will rest in the receptacle 34 and be prevented from sliding out by means of the side 15 of the box 10 until the receptacle 34 has moved downward into a position as shown in Fig. 4, at which time the coin will drop through the opening 19 in the coin box 13. A counter-weight 35 is provided on the opposite 20 end of the arm 33 for the purpose of returning the arm to a high position with respect to the receptacle 34 end, as shown more clearly in dotted lines in Fig. 2. Midway between the receptacle 34 and the front 25 bearing 31, is located a disc 36 securely attached to the side arm 33 and positioned at a point on the arm 33 such that when the arm is in the position shown in Fig. 2, the disk 36 will entirely cover the face of the clock, 30 but when the arm 33 is in the position indicated in Fig. 4, the face of the clock will be uncovered, further illustrated in Fig. 1. Midway along the shaft 32 is a vertically disposed 35 rod 37 adapted to engage with a dog lever 38 journalled in a bearing member 29 attached to the shelf 22, the extreme end of which acts as a stop member so that the dog lever 38 cannot be displaced in a backward direction 40 in the event the entire box 10 is upset. The forward movement of the dog lever 38 is also limited by means of contact against the extension shaft 26. A bracket 39 is attached to the dog lever 38 for the purpose of engaging the pin 30 on the gear 29 contact being 45 had at a point 40 on the bracket 39 better illustrated in Fig. 5. A cut-out portion or opening 41 is provided on said bracket 39 to allow the pin 30 to pass by after having first moved the dog lever 38 out of engagement with the rod 37.

It will be seen that the clock mechanism can be so connected and timed that the gear 29 will, by means of the pin 30, trip the dog lever 38 at a predetermined hour, as for 55 instance 2 a. m. every day and thereby necessitating the insertion of another coin which will in turn throw down the receptacle end of the arm 33 and engage the rod 37 with the dog lever 38 such that the face of the clock 60 will be uncovered until the pin 30 on the gear 29 again engages the bracket 39 thereby closing the face of the clock 22 by means of the disc 36 and counterweight 35. The counterweight 35 is so proportioned in weight that 65 the weight of the smallest coin will counteract

its force and drop the disc 36 unless obstructed by the dog lever 38 and the rod 37 in which event it will raise the disc 36 to the position indicated in Fig. 2.

Having thus described my invention, what I claim as new is:

In a time savings bank, the combination of a casing, a time-piece mechanism located within said casing the face of said time-piece adapted to register with an opening located 75 in the side of said casing, a pivoted screen member mounted to one side of said time-piece mechanism and comprising a lever the extreme end adjacent the said pivot being provided with a counterweight, the opposite end 80 being provided with an openended container adapted to receive and discharge a coin, said coin being discharged from said container by means of gravity acting thereon, the said screen comprising a flat sheet of material 85 mounted in a vertical position between said coin container and said pivot, a locking and release mechanism comprising a gravity operated lever pivoted within said casing at a point adjacent its lower end, the opposite 90 end bent to form a catch, an offset member attached to said gravity operated lever, a lever permanently attached to said screen 95 lever and adapted to engage with said catch on said gravity operated lever for the purpose of maintaining the said screen in an open position following the dropping of a coin in the said bank; a pin member mounted on the time-piece mechanism and adapted to contact periodically with the offset member attached to the said gravity operated member for the purpose of releasing the 100 said permanently attached lever to the said screen lever when engaged by the said catch, substantially as shown and described.

In witness, whereof, I have subscribed my name this 2nd day of October, 1928.

DANIEL L. CHANDLER.
